UNITED STATES PATENT OFFICE.

FRANCIS NAPIER DENISON, OF TORONTO, CANADA.

SHORT-CIRCUITING DEVICE FOR STOPPING DENTAL MOTORS.

SPECIFICATION forming part of Letters Patent No. 543,855, dated August 6, 1895.

Application filed October 9, 1894. Serial No. 525,326. (No model.)

To all whom it may concern:

Be it known that I, FRANCIS NAPIER DENISON, of the city of Toronto, in the county of York, in the Province of Ontario, Canada, 5 have invented certain new and useful Improvements in Short-Circuiting Devices for Stopping Dental Motors, of which the following is a specification.

My invention relates to a short-circuiting device for the instantaneous stoppage of an electric motor more particularly adapted for running a dental engine, and referring particularly to a former application of mine for improvements in dental-motor outfits, filed on 15 the 26th day of May, 1894, under Serial No. 512,537, in which a peculiar construction of foot-switch is used.

The object of the invention is to provide means for short-circuiting the armature of the 20 motor no matter at what rate of speed the motor armature-shaft may be rotating, so as to thereby stop the shaft instantaneously without the necessity of employing any means to decrease the speed of rotation of the armature; and it consists essentially of two contact-plates, preferably arc-shaped in form, insulated from the base-plate of the switch and each connected to the armature of the motor, but separated from each other, and a spring 25 contact-plate connected to the bottom of the toe-plug of the pedal of the foot-switch, which plug is of insulating material, this contact-plate being arranged, when the heel of the 30 pedal of the foot-switch is depressed, to bridge the contact-plates and thus short-circuit the armature no matter into what position the toe 35 may be swung for the purpose of speeding the shaft of the motor, the foot-switch being otherwise constructed as described in my 40 former application above referred to, with the exception that there is no provision made for operating the brake therein provided, which brake, by my present device, is entirely dispensed with.

Figure 1 represents a view, partially in perspective and partially diagrammatic, showing the foot-switch, wiring, motor, hand-switch, shunt-field, and connections, the foot-switch being shown in an enlarged perspective view, 45 a portion of the plate or frame of the switch being broken away. Fig. 2 is a plan view of the rheostat inverted.

For the purpose of clearly illustrating my invention I shall first describe the major portion of the foot-switch in detail, as in my 55 former application, and in so doing will point out the difference in construction necessary to accomplish the present object I have in view.

U is the base plate of the foot-switch, which 60 is made hollow, as shown, and V is the pedal, which is stiffly pivoted, swiveled, and arranged as described in my former application.

U³ U⁸ are hollow stop-pins attached to or forming part of the base-plate U. 65

W is a bar of insulating material secured to the bottom of the base-plate U. A great deal of the bar W is broken away, so as to exhibit details of construction.

X is a bar of insulating material pivoted 70 at the center by the screw-pin x to the bar W.

x' x² are pins which are secured on the ends of the bar X. The pins x' x² extend rearwardly into the slots x³ x⁴, formed at the bottom of the plungers X' X². The plungers X' 75 X² are preferably provided with convex push-ing-caps x⁵ x⁶.

V⁴ is a downwardly-extending plug of insulating material secured to the forward end of the pedal. The plug V⁴ is surrounded at 80 the top by a ring V³ of insulating material, which is designed to limit the downward movement of the plug.

v⁹ is a boss formed underneath the heel portion of the pedal V. The boss v⁹ is provided 85 with a rubber cushion V¹⁰, which is designed to limit the downward movement of the heel portion of the pedal.

Y Y are contact-plates, preferably arc-shaped, which are secured to the bottom of 90 the base-plate U and are insulated from it and each other by the plate Y'.

V⁵ is a spring contact-plate secured on the reduced lower end of the plug V⁴ by a nut v⁶ of insulating material. V⁶ is a spring contact-plate rigidly secured at the bottom of the insulating plug V⁴ by the screw v⁵. It will be seen that the plates V⁵ and V⁶ are insulated from one another. 95

The spring-plate V⁵ is normally held in contact with the plates Y Y when the motor is at rest, and the plate V⁶ is held out of contact with one of the plates Z' of the flat rheostat Z, which is situated beneath the base-plate U, 100

except when the foot-switch is pressed at the toe to throw in the motor. The plates Z' are separated from each other and are insulated from the rheostat by the plate Z^2 .

5 Z^3 are the binding-posts of the rheostat, which extend through the insulating-plate into the rheostat. There is one binding-post for each plate, and the posts are connected to the plates by the wires z .

10 $w w'$ are contact-blocks secured at one end of the bar W , and $w^2 w^3 w^4$ are bars flush with the inner side of the bar.

15 $X^3 X^4$ are contact-plates secured to the front side of the pivoted bar X . The plates $X^3 X^4$ have at one end the spring ends $X^5 X^6$, which are continuously held in contact with the contact-blocks $w w'$ secured to the bar W , and at the other spring ends $X^7 X^8$, which are designed to be respectively brought in contact 20 with the bars $w^2 w^3$ or $w^3 w^4$, this depending upon which of the plungers X' or X^2 is pressed down. The rheostat above mentioned, in this instance, as indicated in Fig. 2, has the greatest amount of resistance at the 25 right-hand side, and the resistance decreases from right to left, the left-hand binding-post having no resistance at all.

The left-hand binding-post Z^3 is connected by the wire z' to the contact-bar w^3 . The bar 30 w^2 is connected to the bar w^4 by the wire z^2 .

$W' W^2 W^4 W^5$ are binding-posts of the motor and switchboard circuits which are secured in the bottom of the bar W .

35 $2 2'$ are wires connecting the contact-plate Y with the binding-post W^4 and W^5 .

3 is a wire connecting the wire z^2 and contact-plate w^4 with the binding-post W' .

4 is a wire connecting the contact-block w with the binding-post W^4 .

40 5 is a wire connecting the contact-block w' with the binding-post W^5 .

6 is a wire connected at one end to the screw v^5 and consequently to the contact-plate V^6 , and extending up through the insulating-pin V^4 , underneath the pedal, through the opening v^3 , down through the hollow pin V^3 , as indicated by dotted lines, forward to the binding-post W^2 .

7 is the positive wire through which the 50 current passes ordinarily when the foot-switch is not thrown in, through the wire 9, shunt-field 10, wire 11, and back by the negative wire 12.

When the forward end of the pedal of the switch is pressed down the circuit is completed 55 and passes through the positive wire 7 into the binding-post W^2 , thence by the wire 6 to and through the insulating-plng v^4 , contact-plate V^6 , one of the plates z' of the rheostat, through the rheostat finally on the wire z to the binding-post Z^3 at the left-hand side of the rheostat, the wire z' to the contact-bar w^3 , thence by the contact-plate X^3 to the contact-block w , thence by the wire 4 to the binding-post W^4 , thence by the wire 13 to the motor, 60 through the motor, and by the wire 14 back to the binding-post W^5 , from the binding-post W^5 , by the wire 5, to the contact-block w' ,

thence by the contact-plate X^4 to the contact-bar w^4 , thence by the wire 3 to the binding-post W' , thence by the wire 12 back to, 70 through, and to the switchboard J . The course above described is that shown when the plunger X' is pressed down and the bar X in the position shown.

It will of course be understood that the direction of rotation of armature-shaft will be reversed, as in my former application, and that the nearer the pedal is swung to the left-hand side of the figure, so as to bring the contact-plate V^6 upon the plates nearer the 80 left-hand side, the less the resistance will be (see Fig. 2) and consequently the greater the speed of the motor.

It will now be seen that in order to produce a short circuit through the armature of the 85 motor and stop the rotation of the armature-shaft, the heel of the pedal V may be pressed down so as to bring the contact-plate V^6 upwardly out of contact with the plates Z' , thereby throwing the current entirely out of the 90 foot-switch. The spring contact-plate V^5 , however, is brought against the contact-plates $Y Y$, so as to bridge them, and an induced current will be produced in the armature short-circuit through the wires 14, binding-post W^5 , 95 wire 2', plate Y , contact-plate V^5 , plate Y , wire 2, binding-post W^4 , and wire 13. It will thus be seen that the motor will be really acting as a dynamo for the time being and that an instant stoppage of the armature-shaft will 100 be effected.

By means of the short-circuiting device above described the instant stoppage of armature-shaft can be effected in the same time at the highest speed as well as at the slowest 105 speed. In my device it will also be seen that owing to the slow speed of armature when running at its maximum the short-circuiting of armature can be effected with the fully-magnetized field, as the induced current in the armature has not time to rise to dangerous proportions on account of the armature coming to rest instantaneously.

What I claim as my invention is—

1. The combination with a motor having a 115 shunt field and circuit completed through a foot switch as specified and the foot switch pedal pivoted and swiveled as specified and having a plug of insulating material extending downwardly from the toe portion through which runs the main circuit wire to the spring contact plate designed to be movable upon the plates of a resistance coil, so as to vary the amount of current through the main circuit and consequently the rate of speed of the motor, of two arc-shaped contact plates insulated from each other and each connected to the poles of the armature and a spring contact plate secured near the bottom of the toe plug of the pedal, insulated from the spring contact plate movable upon the plates of the resistance coil, and so arranged that when the heel of the pedal is pressed down such contact spring will be brought into sliding contact 120 125 130

with the arc-shaped plates so as to bridge them as and for the purpose specified.

2. In combination with the motor having a shunt field and a circuit, a foot switch interposed in said circuit and comprising a hollow base plate having a rheostat beneath the same, the series of contacts connecting therewith, the arc shaped contact plates connected with the poles of the armature, and the foot lever pivoted to swing both vertically and laterally,

and having a contact arm for engaging the said series of contacts as the pedal is swung laterally, and a second contact arm for connecting the two arc shaped plates as the pedal is swung vertically, substantially as described. 15

FRANCIS NAPIER DENISON.
